Inventor.

UNITED STATES PATENT OFFICE.

JAMES J. KELLY, OF ALBANY, NEW YORK.

MACHINE FOR DRESSING AND FINISHING SURFACES OF FLOORS.

No. 810,770.

Specification of Letters Patent.

Patented Jan. 23, 1906.

Application filed July 19, 1904. Serial No. 217,285.

To all whom it may concern:

Be it known that I, JAMES J. KELLY, a citizen of the United States, and a resident of Albany, in the county of Albany, State of New York, have invented a new and useful Machine for Dressing and Finishing Surfaces of Floors, of which the following is a specification.

This invention relates to machines for dressing and finishing surfaces of floors by means of revoluble tool-holding devices carried by a frame provided with carrying-wheels, which frame is moved and guided by means of a handle having on its upper portion means for supplying and transmitting power to the revoluble floor-dressing devices carried by the frame below, which device may be made interchangeable and include scrapers, brushes, or, as shown in this application, a sand-papering disk, which are used, respectively, for the performance of their individual functions in their order, still using the same frame and actuating devices for operating the same for giving the desired finish of dressing to a floor-surface.

The objects and purposes of this invention will be clearly understood from the following description when taken in connection with the accompanying drawings, in one sheet, forming a part of this specification, in which—

Figure 1 is a side elevation of this machine with part in section. Fig. 2 is a plan view of the frame, having secured in it the revoluble floor-dressing device, and shows part of the frame of the machine. Fig. 3 is a transverse section taken at line 1, Fig. 1, and shows the revoluble floor-dressing device and its adjuncts and the means for securing said device in the frame. Fig. 4 is a face view of the upper portion of the handle, showing the means for supplying and transmitting power to the revoluble device in the frame below and the means for adjusting and securing the same. Fig. 5 is a longitudinal section at line 2 in Fig. 2 with the revoluble floor-dressing mechanism removed.

The same letters of reference refer to the same parts throughout the several views.

In the drawings, A, Figs. 1, 2, 3, is a suitable traveling frame for supporting the revoluble floor-dressing parts of the machine. The frame A is composed of the upper and lower halves a a', with hinges B connecting them at their forward ends. The rear end of half portion a' has secured to it the handle-socket C by means of bolts c c, and a lever-

button D is pivoted on the face of socket C for securely holding the two halves of the frame together when the revoluble devices are in place for operation. Coinciding half-bearings z z' are provided in the lower and upper edges, respectively, of frame portion a and a', which receive the journals w of the carrying-wheels W, as shown in Figs. 1, 2, and 5. Notches e are also provided in upper edge of frame portion a' to receive the latches which secure the revoluble floor-dressing devices in place in frame A.

The handle F, Figs. 1, 2, and 4, is preferably made of wood and secured to the frame by means of the socket D, which receives the lower ends of same and is securely held in place by means of bolts f f, as shown in Figs. 1 and 2. The upper end of handle F, Fig. 4, terminates in a knob K, of horn or other suitable form, for conveniently propelling and guiding the machine. An adjustable bracket G, through which passes the journal h of drive-sprocket H, is secured to the handle F, as shown in Fig. 1, and is adjustably secured to the handle by means of bolts I, with thumb-nuts i. A slot J is provided in handle F, through which passes the adjusting-bolts I I, and wear-plates k k are secured to the face side of the handle, as shown in Figs. 1 and 2. Drive-sprockets H H are secured to either end of the journal h, one of which is provided with a crank h'. These drive-sprockets transmit motion to the revoluble floor-dressing devices secured in frame A by means of drive-chain L, as shown in Fig. 1, and the power is imparted by means of crank h', secured to one of the drive-sprockets H. An eccentric l, provided with hand-lever l', is applied to the handle F, Figs. 1 and 4, and bearing against the under side of bracket G is used to take the unnecessary slack out of the drive-chain L. Its pivot is the bolt l', which passes through the slot J in handle F, and is secured by a nut against a wear-plate 100 on the under side of handle F. This eccentric also acts as an auxiliary brace to the bolts I I for retaining the bracket G in place when power is applied to the drive-chain.

The floor-dressing mechanism which I use in this invention consists of the horizontally-revolving disk M, shown to carry a sandpapering-surface m, Figs. 1, 2, and 3, although other interchangeable plates may be applied to the disk M, adapted to carry scrapers, brushes, or other floor-finishing tools. (Not shown.) The tool-carrying disk M is pro-

vided with a vertical shaft N, having on its upper end the miter-gear n , which works in bearing n' in yoke P. Miter-gears n^2 n^2 impart motion to miter-gear n by means of sprocket Q, through short shafts q, which are revolved by drive-chain L, actuated by drive-sprockets H, as shown in Fig. 1. A groove is made on the upper end of vertical shaft N, which is entered by the point-screw n^3 in hub of horizontal miter-gear n , (shown in Fig. 3,) which allows the disk M to have movement vertically, and the shaft is made elastic by means of the spiral tension-spring O. (Shown in same figure.) The yoke P, in shape and proportions as shown in Figs. 1, 2, 3, and 5, serves to support the shaft N in a vertical position and has a bearing n' , and each limb is provided with feet p p, which rest on the ends of transverse member R.

20 S is a clip having its free ends turned in toward one another, which, as shown in Figs. 2, 3, and 5, serves to securely bind the yoke P and transverse piece R together and allow passage for the holding-latches T. The holding-latches T pass between transverse member R and the lower part of clip S, projecting beyond same a distance equal to the thickness of sides of frame A and are secured by set-bolts s. Bolts r pass through the clip

25 S, feet p of yoke P, and transverse member R, securely holding them together, as shown in Figs. 1, 2, 3, and 5. Short transverse shafts q, which are in alinement with drive-sprockets H, having on their outer ends sprockets Q, are passed through lugs a' on upper half-frame portion a, then through the limbs of yoke P, Figs 1, 2, and 3, into the hubs of the vertical miter-gears n^2 , terminating at the vertical shaft N, and both the horizontal and

30 vertical shafts have bearing in the cross-form sleeve X. (Shown in Fig. 3.) The miter-gears n^2 are secured to the shaft q by screws or pins, as shown in same figure.

The manner in which the machine is set up

35 is as follows: The hinged frame A, provided with handle F, secured to said frame, as described, is opened by throwing over the latch D free of the upper half a and swinging the half-frame member upward and forward.

40 Then the revolving floor-dressing device last above described is inserted in place, with the holding-latches T resting in notches e, Fig. 1. The carrying-wheels W are placed with their journals w resting in half-bearings w', Fig. 2.

45 The upper half-frame a is then swung back into place and the button-lever thrown to a vertical position, as shown in Figs. 1 and 2, securely locks the floor-dressing parts to the carrying-frame. Then the bolts I, Figs. 1

50 and 4, as well as the pivot-bolt l, are loosened by turning the nut and thumb-nuts of same, and the bracket moved downward enough to allow the drive-chain L to be passed over sprocket Q of the floor-dressing mechanism

55 and the drive-sprocket H. The bracket G

is then slid upward approximately to its proper place and then permanently adjusted by turning the lever eccentric l. The thumb-nuts i i are then tightened and the machine is ready for operation. It is to be understood that previous to its insertion in the carrying-frame the disk M has secure to its under surface either the applied sandpapering device, as shown in the drawings, or the other interchangeable floor-dressing device, as 75 scrapers or brushes before mentioned, but not shown.

Although the drawings show a crank h^2 , provided on one of the drive-sprockets H, for adjusting the working parts of the machine 80 by manual power, yet the crank may be dispensed with and any other suitable power, as of electric motor, compressed-air, or vapor engine, be used to the same purpose. The frame A, provided with its handle and adjuncts for supplying power, is adapted to readily receive or release the operating parts of the revoluble floor-dressing device, which may be fitted with such interchangeable surfacing-tools as the nature of the work may 90 require in dressing or surfacing a floor, and this machine, complete in itself, obviates the use of several separate machines for work of this nature.

Having described my invention, what I 95 claim, and desire to secure by Letters Patent, is—

1. In a machine of the class described, the combination with a main frame composed of two parts hinged together, and formed with 100 grooves, means for locking the two parts together, wheels having axles supported in the grooves, a handle, a supplemental frame carried by the main frame, a revolving floor-dresser, gearing for revolving the floor-dresser, power means on the handle for operating the gearing, and means on the handle for adjusting the power means.

2. In a machine of the class described, the combination with a separable main frame, a 110 detachable supplemental frame carried by the main frame, means for locking the supplemental frame to the main frame, a revolving floor-dresser mounted in the supplemental frame, means for revolving the floor-dresser, supporting-wheels mounted on the main frame, and a handle for guiding the machine.

3. In a machine of the class described, the combination with a main frame made in sections which are hinged together, a supplemental frame supported by the main frame, locking devices for locking the supplemental frame to the main frame, a vertically-movable and rotatable shaft mounted in the supplemental frame, a floor-dressing device carried by the vertical shaft, a spring normally depressing the dressing device, a gear meshing with the gear on the vertical shaft, a handle, and means on the handle for impart- 125

ing motion to the gear to revolve the dressing device.

4. In a floor-dressing machine, the combination with a frame, a dressing device supported on the frame, gears for operating the dressing device, a handle connected to the frame, means mounted on the handle, for op-

erating the gears, an adjustable support for said means, and a cam for locking the support after it is adjusted.

JAMES J. KELLY.
